HIGH-FREQUENCY ELECTRICAL SWITCH
AND CONTACTOR SYSTEMJoseph F. Frese, Baltimore, Md., assignor to
The Monitor Controller Company, Baltimore,
Md., a corporation of Maryland

Application March 1, 1944, Serial No. 524,594

8 Claims. (Cl. 174—140)

My invention relates broadly to high frequency electrical apparatus and more particularly to a construction of high frequency potential equalizer for association with the contactors of electrical switches and stand-off insulators in high frequency electrical systems.

One of the objects of my invention is to provide an improved construction of corona shield for high potential, high frequency electrical apparatus.

Another object of my invention is to provide a construction of high potential, high frequency terminal unit for association with electrical contactors or stand-off insulators in high frequency systems for reducing discharge losses to a minimum.

Still another object of my invention is to provide an improved construction of high potential surface equalizer for association with contact members of high potential, high frequency switches and/or stand-off insulators in high frequency systems for reducing brush discharge losses to a minimum.

A further object of my invention is to provide an improved construction of streamlined high potential, high frequency unit for improving electrical efficiency in high frequency, high potential circuits by maintaining discharge losses at circuit connection or terminal positions at a minimum.

Other and further objects of my invention reside in an improved construction of substantially toroidal shaped high frequency unit which may be produced on a quantity production basis at relatively low cost embodying structural features of novelty set forth more fully in the specification hereinafter following by reference to the accompanying drawings, in which:

Figure 1 represents one application of the potential equalizing device of my invention showing the manner of using the device as a shield for the contact system of a high potential switch; Fig. 1A is an enlarged longitudinal sectional view illustrating the arrangement of the elements of the device of my invention at the instance of establishing electrical contact in the switch system; Fig. 2 is a view showing the switch system of Fig. 1 in plan and schematically illustrating the actuator; Fig. 3 is an end elevation of the potential equalizing device of my invention looking in the direction of arrow A in Fig. 1; Fig. 4 is a side elevation of the device illustrated in Fig. 3 looking in the direction of arrow B; Fig. 5 is a longitudinal sectional view through the device of my invention on line 5—5 of Fig. 4; Fig. 6 is a longitudinal sectional view through the potential equal-

izer and contact system shielded thereby on line 6—6 of Fig. 3; Fig. 7 is a transverse sectional view through the device of my invention taken on line 7—7 of Fig. 4; Fig. 8 is a transverse sectional view taken on line 8—8 of Fig. 4; Fig. 9 is side elevational view of the shell of the potential equalizing device with parts broken away and illustrated in section; Fig. 10 is a vertical sectional view taken on line 10—10 of Fig. 11; Fig. 11 is a vertical sectional view taken on line 11—11 of Fig. 9; Fig. 12 is a horizontal sectional view taken on line 12—12 of Fig. 9 looking in the direction of the arrows; Fig. 13 is a transverse sectional view taken on line 13—13 of Fig. 9; Figs. 14, 15, 16 and 17 are views showing the construction of contact holder or plug which is employed in the device of my invention; Fig. 18 illustrates in side elevation the application of the potential equalizer of my invention to a stand-off insulation with parts broken away and shown in section; and Fig. 19 is a plan view of the potential equalizer illustrated in Fig. 18.

Referring to the drawings in detail, reference character 1 designates an insulated support 25 which may be a stand-off insulator of suitable insulation material such as Micalex or glass mounted in any suitable manner. The end of the insulated support provides a mounting means for the high frequency, high potential voltage equalizing surface member which consists of a substantially toroidal-shaped structure modified to substantially conform with the contour of the supporting insulator 1. The high frequency, high voltage terminal unit comprises a pair of symmetrically arranged members which I have designated at 2 and 3, each apertured at 2a and 3a for the passage of the end of the insulated support 1. The symmetrically arranged parts 2 and 3 may be formed from a sand casting of cast brass although other metallic material may be employed. 30 The parts 2 and 3 which fit together along a central dividing axis are substantially hollow except for central diametrically extending portions represented at 2b and 2c, and 3b and 3c. The curvature of the two substantially hollow members 2 and 3 is such that the surfaces are formed on a minimum radius of three-fourths of an inch and the exposed surface is a minimum for operation at high voltages without appreciable corona 35 or electrostatic discharge.

The substantially hollow members 2 and 3 each have relatively thin walls of the order of one-eighth of an inch which abut edge to edge as indicated at 2d and 3d forming a tight seam. The 40 abutting edges 2d and 3d may be ground to form:

a substantially invisible seam or coacting joint and they are subsequently secured to each other by a process of welding, brazing, soldering or other manner.

The rounded and curved surface members 2 and 3 in the form illustrated in Figs. 1-17 inclusive are arranged for protecting an electrical contact of a high frequency switch and in this form of my invention the parts 2 and 3 are somewhat modified and elongated from true toroidal shape and recessed at the end, providing a pair of substantially parallel extending portions forming a pocket-like enclosure at one end of the device for electrically shielding an electrical contact device. End portions 2c and 3c are provided with end recesses 2e and 3e which when aligned coact to form a substantially square recess having rounded corners. The solid portions 2b and 3b of the potential equalizing device integrally connect with inner wall portions 2h and 3h which unite edge to edge forming an abutting inner surface against which the outer surface of insulator 1 abuts. The edges 2h and 3h are centrally apertured at 4 to permit the introduction and passage of a securing bolt 5 having a head 6 and a screw threaded end 7. The insulated support 1 has a transverse aperture 8 therein through which bolt 5 after passing through lock washer 9 and aperture 4 extends, projecting centrally into the contact carrying plug 10. The contact carrying plug 10 extends into the substantially square recess formed by the coacting portions 2e and 3e and is secured therein by engagement between screw threads 11 formed internally in the plug 10 and screw threads on the end of bolt 7. The assembly is effected by fastening the corona shield to the insulated support 1 before the tubular connector 22 is placed into the socket formed by coacting parts 2b and 3b. This permits connecting bolt 5 to be passed through aperture 4 and engaged in threads 11 in plug 10. Thereafter connector 22 is secured to the socket in the corona shield. The plug 10 serves as a holder for the contact element 12 which is mounted in the lug portion 14 of the plug as shown. The lug portion 14 is apertured and shaped at 15 for receiving the contact support 16 which is relatively adjustable in the contact holder in order to present a plane surface for contact by the face of the movable contact designated at 17 carried by switch arm 18. The adjustable contact 12 is maintained in position through spring member 19 which exerts pressure between the countersunk recess 20 in the contact holder 10 and the headed end 21 of the adjustable contact. Thus the adjustable contact 12 may be angularly shifted in that position in which good electrical contact is established as the movable contact 17 is brought into contacting relation therewith. To insure good electrical connection between the potential equalizing device, the adjustable contact 12 and the electrical connector 22 which enters the socket formed by aligned semi-cylindrical recesses 2f and 3f, I provide a flexible strip-like connector 23 extending from a position beneath contact 12 into the grooved recess 24 beneath the solid portion 2c of the potential equalizer. A set screw 25 extends through the potential equalizer and clamps the connector strip 23 in position therein, thus establishing good electrical connection.

The electrical connector 22 is retained in the socket formed between the solid portions 2b and 3b of the potential equalizing device by set screw 26 which extends through a threaded aperture 27

in the solid portion 3b and engages the tubular member constituting the electrical connector 22.

In Figs. 1 and 2 I have shown one form of actuator for the switch system with which the corona shield of my invention is associated. It will be seen that a panel structure 28 is provided from which the stand-off insulator 1 extends. The stand-off insulator 1 may be of Micalex, glass or other form of high frequency insulator and may be mounted in a socket member 29 which is cemented as represented at 30 in the socket member 31 suitably secured to the panel 28 by bolts 32. The switch actuator includes lever actuating mechanism 33 journaled in standards 34 extending from panel 28. The lever actuating mechanism is operated from shaft member 35 journaled in standards 36 supported from panel 28. Shaft 35 is controlled by an operating magnet shown generally as housed within casing 37. The operating magnet is arranged to angularly shift shaft 35 which initiates in operation power control switch indicated at 38 and time control mechanism indicated at 39 while imparting angular movement to the motion multiplying lever mechanism represented at 33. The switch 38 is generally of the single pole single throw type for controlling a power supply circuit. The time control mechanism 39 is generally employed for controlling circuits to electron tubes or other devices where it is desirable to complete a circuit through resistors in predetermined time relation to the other functions carried out by the switch system of my invention.

The principal reason for illustrating the potential equalizing device as formed as a substantially hollow body is to save weight and material which would otherwise be employed in constructing the potential equalizing device. When it is realized that the potential equalizer even for moderate voltage installations may have over-all dimensions of approximately $5\frac{1}{4} \times 4\frac{1}{2} \times 2\frac{1}{2}$ ", it will be appreciated that a solid mass of metal of this size will have appreciable weight which is substantially reduced by the shell-like contour of my invention.

In Figs. 18 and 19 I have shown my invention applied to a stand-off insulator by which conduits or electrical connectors shown at 40, 41, 42 and 43 are interconnected. Set screws 40a, 41a, 42a and 43a extend through one or the other of the shells 44 and 45 for clamping the tubes or electrical connectors 40, 41, 42 and 43 in position. It will be observed that the sections 44 and 45 are symmetrical in the case of the stand-off insulator application and not elongated as in the case of the electrical contact shield application. The coacting sections 44 and 45 are modified from true toroidal shape but are apertured centrally for the passage of the stand-off insulator 1 therethrough. Bolt member 46 which passes through apertured internal end walls in the diametrically opposite sockets formed between the coacting members 44 and 45 serves to secure the potential equalizing device adjacent the end of the stand-off insulator. I have shown connecting means for four electrical connectors but it will be understood that the stand-off insulator may be employed for connection of but two electrical connectors in which event socket portions are omitted from the structure of the shells constituting the potential equalizing device.

The structure of the corona shield is such that substantial weight is saved, thereby making the structure useful as a stand-off insulator without

increasing mechanical supporting difficulties in an assembly requiring a number of these units in relatively close proximity. I have successfully employed the corona shield with minimum radius of approximately $\frac{3}{4}$ and approximately 8" break and clearance distance between the shield and the contact arm in systems where the corona discharge voltage has been in the range of 80,000 volts while flash-over has occurred in the range of 83,000 volts. The use of the corona shield has improved efficiency of the system by allowing continuous operation without flash-over at high voltages. In some of my earlier tests of the structure described herein using a smaller radius of approximately $\frac{1}{2}$ " and a break and clearance distance between the shield and the contact arm of approximately 6", audible and visible corona discharge started at about 50 kv. R. M. S. at 60 cycles. Flash-over occurred at 60 kv. R. M. S. at 60 cycles between the stationary contact 12 and the movable contact 17 on the movable contact arm 21. The test was conducted at a barometric pressure of 30.04 in Hg and temperature of 19.0° C. and relative humidity of 36%. The earlier tests were made where the minimum radius of the potential equalizing surface was approximately $\frac{1}{2}$ " and break and clearance distance of approximately 6". When this minimum radius was corrected by enlarging it to approximately $\frac{3}{4}$ " and increasing the break and clearance distance to approximately 8" as explained hereinbefore, a further series of tests showed audible and visible corona discharge starting at 80 kv. R. M. S. 60 cycles with actual flash-over occurring at 83 kv. R. M. S. 60 cycles. These tests were conducted using the device as a contactor. Other tests made when using the device as a stand-off insulator gave even higher readings than those set forth above, as for example, certain stand-off insulator tests where visible and audible corona discharge started at 89 kv. R. M. S. 60 cycles and actual flash-over occurred at 93 kv. R. M. S. 60 cycles. Accordingly, it will be seen that the structure of my invention provides very substantial protection both as a contactor device and as a stand-off insulator device.

The figures given above respecting the approximate $\frac{3}{4}$ " radius and approximate 8" break are for devices where the discharge voltage is in the range of 80,000 volts while flash-over voltage is in the range of 83,000 volts. When the discharge voltage is reduced it is possible to reduce the approximate radius of the parts of the corona shield to approximately $\frac{1}{2}$ " for approximate breaks of 6". The dimensions given are relative and are cited as examples of statistical data which I have accumulated in the course of the research and development of my invention.

While I have described my invention in certain of its preferred embodiments, I desire that it be understood that modifications may be made and no limitations upon my invention are intended other than may be imposed by the scope of the appended claims.

What I claim as new and desire to secure by Letters Patent of the United States is as follows:

1. A corona shield comprising in combination with an insulated supporting post, a pair of substantially hollow metallic shell members each apertured to fit over the end of said post and electrically connected edge to edge to form an equi-potential surface, a socket recess formed intermediate the adjacent edges of said members at one end thereof, a circuit terminal extending into

said socket recess, means extending through one of said members for securing said circuit terminal in the socket recess, and an electrical contact device carried by said members adjacent the opposite end thereof, said contact device being electrically shielded by said members.

5 2. An equi-potential surface device comprising in combination with a supporting post of insulation material, a pair of shell-like substantially hollow members mounted edge to edge and centrally supported by said post, said members being symmetrically recessed at one end for receiving an electric circuit terminal and being symmetrically recessed at the opposite end for receiving an electrical contact device, said members projecting beyond the limits of said contact device and operating to electrically shield said contact device.

10 3. An equi-potential surface device comprising in combination with a post of insulation material, a pair of substantially hollow shell-like members having means disposed centrally thereof for engaging said post, said members extending a greater distance beyond one side of said post than beyond the other side of said post and forming a socket recess on said latter side for a circuit terminal and a socket recess on said former side for an electrical contact, a circuit terminal extending into said first mentioned recess, and an electrical contact support extending into said second mentioned recess, and means extending through one of said members for securing said circuit terminal in said first mentioned socket recess and securing said contact device in said second mentioned socket recess.

15 4. An equi-potential surface device comprising in combination with a post of insulation material, a pair of substantially hollow shell-like members each having means engaging said post, said members being electrically connected edge to edge to establish a streamlined surface projecting a greater distance on one side of said post than on the opposite side of said post, a socket recess formed in said members on the side which projects the shorter distance from said post for receiving a circuit terminal therein, a socket recess formed in said members at the opposite side of said post for receiving an electrical contact device mounted in said electrical contact support in a position substantially within the limits of the projecting end of said members.

20 5. An equi-potential surface device comprising in combination with a post of insulation material, a pair of substantially hollow shell-like members electrically connected edge to edge and supported by said post, said members forming a socket recess in one end thereof adjacent said post, an electrical circuit terminal projecting into said recess, means for securing said electrical circuit terminal therein, the opposite ends of said members being centrally recessed and forming a socket intermediate said last mentioned recessed end and said post, a contact holder having a plug-like portion extending into said last mentioned socket, a projection on said plug-like portion, and a contact carried by said projection in a position substantially within the limits of said members.

25 6. An equi-potential surface device comprising in combination with a post of insulation material, a pair of substantially hollow shell-like members electrically connected edge to edge and supported by said post, said members forming a socket recess in one end thereof adjacent said post, an electrical circuit terminal projecting into said recess, means for securing said electrical circuit

terminal therein, the opposite ends of said members being centrally recessed and forming a socket intermediate said last mentioned recessed end and said post, a contact holder having a plug-like portion extending into said last mentioned socket, a projection on said plug-like portion, and an angularly shiftable contact device carried by said projection and movable to selected planes substantially within the limits of said members.

7. A corona shield comprising in combination with an insulated post, a pair of coacting metallic members connected edge to edge and supported by said post, said members each having rounded external surfaces formed on radii of not less than approximately $\frac{3}{4}$ of an inch for voltages in the range of 80,000, said surfaces extending a greater distance on one side of the supporting post than on the other side thereof and forming a pair of substantially parallel projecting electrically

shielding surfaces, and a contact device supported by said coacting members and extending between said pair of projecting portions of said parallel projecting electrically shielding surfaces.

5. 8. A corona shield comprising in combination with an insulated post, a pair of coacting metallic members connected edge to edge and supported by said post, said members each having rounded external surfaces, said surfaces extending a greater distance on one side of the supporting post than on the other side thereof and forming a pair of substantially parallel projecting electrically shielding surfaces, and a contact device supported by said coacting members and extending between said pair of projecting portions of said parallel projecting electrically shielding surfaces.

JOSEPH F. FRESE.
